UNITED STATES PATENT OFFICE.

HENRY S. WING, OF ASHTABULA, OHIO, ASSIGNOR TO JENNIE A. WING,
OF SAME PLACE.

CARRIAGE-BOW.

SPECIFICATION forming part of Letters Patent No. 257,262, dated May 2, 1882.

Application filed January 19, 1882. (No model.)

To all whom it may concern:

Be it known that I, HENRY S. WING, of Ashtabula, in the county of Ashtabula and State of Ohio, have invented certain new and useful 5 Improvements in Carriage-Bow Sockets; and I do hereby declare the following to be a full, clear, and exact description of the invention, such as will enable others skilled in the art to which it pertains to make and use the same.

10 My invention relates to an improvement in carriage-bow sockets, the object of the same being to provide a strong and durable socket that can be attached to any covered vehicle, and one that is adapted by its peculiar construction to receive and retain a covering of leather or any other suitable material, and removably hold the same in position.

With these ends in view my invention consists, first, in a carriage-bow socket made of 20 spring metal bent in the form shown and provided with a covering of leather or any suitable material, of a wedge or block adapted to be inserted between the adjacent edges of the socket and hold the covering securely in position.

25 My invention further consists, in a carriage-bow socket made of spring metal bent in the form shown and provided with a covering of leather or any suitable material, of a wedge or block inserted between the adjacent edges of the socket to hold the covering in position, and buttons the shanks of which are adapted to pass through one side of the socket-iron and hold the wedge in position.

30 My invention further consists in certain details in construction and combinations of parts, as will be more fully explained and pointed out in the claims.

In the accompanying drawings, Figure 1 is 40 a view in elevation of my improvement, with the leather covering broken away to show the construction of the socket. Fig. 2 is a transverse sectional view of the same, and Fig. 3 is an enlarged view of the wedge.

45 A represents the upright portion of a carriage-bow, provided at its lower end with any suitable slot-iron, A', for its attachment to the body of the vehicle, and at its upper end with a socket or opening for reception of one end of 50 the curved bow B'. The upright portion A

is made of sheet-steel, of any suitable length and width, bent in the form of the letter C, so that the two opposite edges, a a, will lie close together and form spring-jaws, for the purpose to be hereinafter described.

55 One of the main features of my invention, as heretofore stated, is to provide means for securely holding the leather or suitable covering, B, in position on the piece A. Heretofore these bow-sockets have been covered by 60 leather sewed thereon by hand; but this method is tedious and expensive, and the bow when finished does not present a neat appearance.

65 The manner of securing the covering to my bow is as follows: The leather or suitable covering material is first cut the desired width, and then folded or placed around the spring A, and the opposite edges thereof passed between the opposite edges of the spring A. After it has been smoothed down and stretched 70 tight the wedge C is introduced between the edges a a and pressed home. As this wedge C is moved inward it bears against the turned edges of the leather covering B and draws it firmly around the spring or socket A and holds 75

it securely in position. This wedge C, before referred to, can be made of wood, metal, or any desired material, and of any desired shape best suited for the purpose; but I prefer to construct it of wood, as it answers all purposes 80 satisfactorily, and of the shape shown in the drawings, as it is very well adapted for the purpose in view. In this construction of wedge or key the lower or inner edge thereof is made slightly smaller than the space between the 85 edges a a, so that it can be introduced into the space without the necessity of separating the edges of the spring A for the purpose.

The sides of the wedge C continue to incline outward until the point c is near the outer 90 edge thereof, when they incline inward for a short distance. The wedge is provided with the facing of metal, stiff leather, or any suitable material, to prevent the wedge from entering too far into the socket.

95 By constructing the wedge as above described it is prevented from working loose, as the shoulders or projections c form a locking-bearing and effectually prevent the wedge from moving in any direction.

125

D is a curtain or other suitable button, provided with a pointed or screw-threaded shank, which latter is adapted to pass through the side of the socket A opposite the inner end 5 of the wedge C, and find a seat in the said wedge. This button, besides being seated in the wedge C and serving the ordinary functions of curtain-buttons, also assists in holding the wedge in position and prevents it from being removed until the buttons have been withdrawn.

I would have it understood that I do not limit myself to the exact form of the spring-socket A nor wedge C, as they are capable of 15 being constructed in a number of different ways to accomplish the same result; but I consider myself at liberty to make such changes as come within the spirit and scope of my invention.

20 Having fully described my invention, what I claim as new, and desire to secure by Letters Patent, is—

1. The combination, with a spring-metal carriage-bow socket bent in an oval or any suitable form, with its side edges slightly sepa- 25

rated, and a leather or any suitable covering the side edges of which are turned over the adjacent side edges of the socket, of a wedge or key adapted to be introduced between the adjacent edges of the socket and hold the covering in position. 30

2. The combination, with a spring-metal carriage-bow socket bent in the form shown, and a leather or any suitable covering the side edges of which are turned over the adjacent 35 edges of the bow-socket, of a wedge adapted to be introduced between the said adjacent edges of the spring-metal socket and hold the covering in position, and curtain-buttons the shanks of which pass through one side of the 40 socket and enter the wedge and hold the same in position.

In testimony whereof I have signed this specification in the presence of two subscribing witnesses.

HENRY S. WING.
